GOLF PRACTICE DEVICE

Vernon D. Sell, Kansas City, Mo.

Application April 8, 1946, Serial No. 660,391

1 Claim. (Cl. 273—35)

1

This invention relates to game devices and particularly those relating to the type adapted for practicing the game of golf, and the primary object of the invention is to provide such an apparatus wherein is embodied an unique and novel backstop having a plurality of openings formed therein so that the skill of directing the golf ball with respect to its loft and direction of travel is developed.

One of the important objects of this invention is to provide a game having a substantially pyramidal backstop, the walls thereof are disposed at angles with respect to the position of the player to more closely simulate conditions met in playing the regular game, thus teaching the player virtually all the strokes and positions necessary for efficiency in the conventional game of golf.

Other aims of this invention include the provision of a device for practicing the game of golf having a backstop provided with a plurality of openings of different size and disposition to receive the driven ball whereby the player may compute his score and determine the extent of his progress; the provision of deflectors behind each opening for keeping the driven balls that pass through the openings within a relatively close range to the game device for facilitating the retrieving thereof; and the inclusion of supporting means for the backstop, disposed in such manner that there is little danger of the balls striking that part of the structure.

A yet further object of the invention is to provide specific and novel apparatus for embodying the same, which apparatus will be cheap to manufacture, strong, durable, and free from parts likely to become maladjusted.

Other objects of the invention will appear during the course of the following specification, referring to the accompanying drawing, wherein:

Figure 1 is a perspective view of a game device embodying the present invention.

Fig. 2 is a vertical section through the same, taken on line II—II of Fig. 1, and,

Fig. 3 is a fragmentary, cross sectional view taken on line III—III of Fig. 1.

It is well known in this art that practice is required to attain skill in directing a golf ball with respect to both its line of travel and loft. Many games wherein the player strikes a golf ball are on the market, but none include features whereby the various iron and wood clubs are employed for a specific purpose and in a manner to teach the player proficiency in their use.

It is the broad general object of this invention

2 to provide a game of the aforementioned nature, and one embodiment of the same, shown in the drawings, includes a substantially pyramidal backstop broadly designated by the numeral 10, constructed of heavy canvas or duck and stretched taut so that the balls will strike a yieldable surface when they hit any one of the several walls thereof. Backstop 10 comprises a substantially triangular top wall 12 and similarly formed side walls 14 and 16 respectively, all of which walls diverge from a common point to form a three-sided frusto-pyramidal structure as clearly illustrated in Fig. 1. The side walls 14 and 16 are opposed and joined to the top wall 12 as at 18. The three walls are held in operative position by framework comprising spaced-apart, upright posts 20 and 22 and a horizontal crossbar 24. Suitable cords or analogous fastening means 26 hold the walls in place within the said supporting framework.

Each of the walls 12, 14 and 16 is provided with a centrally disposed aperture designated by the numerals 28, 30 and 32 respectively, and an opening 34 is defined by the rear edges of said walls at the vertex of the backstop 10 to receive golf balls that are accurately driven therethrough. A planar target 36 having an aperture 37 is suspended within the opening 34 and is appreciably smaller in area than the opening 34 whereby to present open space therearound to receive balls directed toward the aperture 37 but not accurately directed to enter aperture 37.

Positioned behind each of the aforesaid apertures 28, 30 and 32 and opening 34 and aperture 37 are suitable deflectors for impeding the travel of golf balls passing through these several openings for causing the ball to fall behind backstop 10 within a relatively small area to facilitate retrieving of the balls for further use. With respect to the opening 34 and the aperture 37 through the target 36, a flap 38 extends outwardly from the top wall 12 and downwardly to lie directly behind the opening 34 and aperture 37. Additional framework 40 is employed as illustrated in Fig. 2 for holding the flap 38 in position and for cooperating with post 20 and 22 and crossbar 24 to hold the walls of backstop 10 in taut condition.

A flap 42, extending outwardly from each of the walls 14 and 16 respectively, is supported at its free end by an upright post 44 and constitutes a deflector for balls entering the apertures 30 and 32. The deflector for balls entering the aperture 28 comprises an open-bottom pocket 46 carried by the top wall 12, preferably of wire

mesh or other suitable material capable of self support to maintain an open pocket behind the aperture 28.

In order to develop the art of direction and to permit driving the balls to a given opening the player may either attempt to drive the balls directly into the opening which he selects or cause the same to deflect from one of the sloping walls and then into the selected opening. The size of the device will vary according to the area of 10 the range available for such practice and according to the size of enclosure if constructed for use indoors. Similarly the openings through which the balls are driven will depend in size and disposition upon the conditions and location 15 of the game.

Any one of the various clubs commonly used in the game of golf may be selected for practice with this device. For instance, the player having difficulty in the manipulation of the putter 20 will attempt to drive balls through opening 34. The degree of loft or angle of the face of the club will determine the opening which the golfer selects as the target toward which he will attempt 25 to drive the ball. Apertures 30 and 32 will be used as a goal when playing the mid-iron or mashie, while aperture 28 is particularly suited for the niblick or the number 8 or 9 iron, all in accordance with the particular difficulties the golfer may be having in his game with respect 30 to hooks, undercuts, slices, overdrives, etc.

Manifestly any number of rules may be set up with the use of this device such as designating a ball driven through the aperture 37 in the target 36 as a hole-in-one, the opening 34 as a 35 birdie, and various combinations of openings to constitute a par game. Sand boxes 48, positioned adjacent to the walls 20 and 22 provide additional hazards when balls land therein after 40 striking backstop 10 and failing to enter one of the openings. Driving the balls from these sand

boxes into one of the openings corresponds to the usual type of sand trap found on most golf courses.

Many advantages will arise from the employment of a game device having this invention employed therein, and while a large number of the important features have herein been set down, it will be understood that those made possible by the invention are contemplated thereby.

Having thus described the invention, what is claimed as new and desired to be secured by Letters Patent is:

A device for practicing the game of golf comprising a pyramidal backstop disposed with its axis substantially horizontal and having a plurality of apertured walls of flexible material and an opening formed at the vertex thereof; framework for supporting the walls in taut condition; an open-bottom deflector for each aperture respectively carried by said walls and extending outwardly from one face thereof for changing the path of travel of golf balls passing through said apertures; and a target mounted within said opening, the area of said target being smaller than the area of said opening, said target having an aperture therethrough appreciably smaller than the apertures in said walls.
